UNITED STATES PATENT OFFICE.

JAMES E. HARTMAN, OF COLLEGE SPRINGS, IOWA.

WASHING-MACHINE.

SPECIFICATION forming part of Letters Patent No. 439,243, dated October 28, 1890.

Application filed April 19, 1890. Serial No. 348,640. (No model.)

To all whom it may concern:

Be it known that I, JAMES E. HARTMAN, a citizen of the United States, residing at College Springs, in the county of Page and State 5 of Iowa, have invented certain new and useful Improvements in Washing-Machines; and I do hereby declare the following to be a full, clear, and exact description of the invention, such as will enable others skilled in the art 10 to which it appertains to make and use the same.

My invention has relation to washing-machines, but more particularly to that class in which the clothes are passed between corrugated rollers and corrugated boards; and my 15 object is to produce a more efficient, serviceable, and convenient device than has heretofore been in use.

With this end in view my invention consists in certain peculiarities of construction and combinations of parts more fully described hereinafter, and pointed out in the 20 claim.

Referring to the accompanying drawings, 25 Fig. 1 is a top view of the structure, and Fig. 2 a side elevation with the side of the tub or box broken away to show the interior.

The reference-letter A represents the tub or box for containing the clothes, being mounted 30 on suitable legs a, and provided with a cover B. The tub is lined with a suitable material and its bottom slopes at either end, as seen at b, so that all the water can be drawn off through the outlet C in the bottom of the 35 front side of the tub.

The rollers D and E are mounted in the opposite ends of a frame fitting within the tub between the long sides thereof, and consisting of the side bars F and cross-pieces G, connecting them intermediate of the rollers. Both 40 rollers are corrugated lengthwise, and the ribs d of the roller D are made straight, while the ribs e of the roller E have a spiral form, as will be seen more clearly in Fig. 1.

The shaft H, on which the smaller roller D is mounted, simply extends into the side bars of the frame, thus leaving the lower end of the frame free; but the shaft I of the larger roller E passes through said side bars and 45 into the sides of the box, thus also constituting a pivot for the frame. The roller E is rigidly mounted on this shaft I, and one end

of the latter extends through the side of the tub and is bent up to form a crank-arm J, having a suitable handle J'. Thus the turning of the crank will cause the revolution of 55 large roller, and this motion will be imparted to the smaller one through the medium of the ropes K, which pass around both rollers and work in peripheral grooves L in the same. 60 These ropes are preferably three in number, and each one has attached to it a number of loops M, in which pieces of clothes are fastened, to be carried around. Behind the larger roller is situated a wash-board N, having a 65 corrugated face O, and pivoted by means of its legs P to the base of the sides of the tub, as seen at p in Fig. 2. A coil-spring Q is interposed between the back of this board and the end piece of the tub, and will thus give 70 the board a spring-pressure against the roller, and hence allow it to adjust itself to material passing between them. The spring is supported and held in proper position by means of transverse strips R S, secured to the board 75 and tub, respectively, the strip S being provided with a depression or groove s, in which the end of the spring drops. It will thus be seen that the spring is readily removable. Beneath the smaller roller a loose wash-board 80 T is placed, which rests upon the bottom of the tub, and is provided with end pieces U, bearing against the end of the tub to keep the board in proper position. The roller will then have free access to rub the clothes between it and this loose board, and will adjust 85 itself to the material passing through. As it has been previously stated, the lower end of the frame is free of the tub, and can move up or down on its pivot I. A further advantage of 90 this arrangement is that if the clothes become caught underneath or the loose board slips from its place the frame can be elevated to the position shown in dotted lines in Fig. 2, and thus access gained to the bottom of the 95 tub, which is advantageous for divers reasons.

The operation will now be apparent, and needs but little description. The pieces of clothes to be washed will be attached in the loops M, secured to the ropes K, and the cover 100 shut, when the crank will be turned and the clothes thus carried around between the two rollers and their respective boards and rubbed through between them, it being understood

that water has been previously introduced into the tub. When the clothes have been sufficiently treated, the roller-frame can be thrown up and the pieces removed and others substituted. Thus a simple and convenient structure is produced, which at the same time is efficient in its working and thoroughly rubs and cleans the clothes in a short space of time, as they pass successively from one set 10 of rubbers to another.

It is evident that my device might be varied in many slight ways which might suggest themselves to a skilled mechanic, and hence I do not wish to confine myself to the 15 precise construction and arrangement herein shown, but consider myself entitled to all such slight variations as come within the spirit and scope of my invention.

Having thus described my invention, what 20 I claim as new, and desire to secure by Letters Patent, is—

In a washing-machine, the combination of a frame contained within the clothes-receptacle, a pivot extending through said frame and journaled in the sides of said receptacle, a 25 corrugated roller rigid on said pivot, a wash-board pivoted back of said roller and having spring-pressure against it, a stationary wash-board on the bottom of the receptacle, a gravitating corrugated roller mounted in the opposite end of said pivoted frame directly above said stationary wash-board and adapted to rest upon it, and suitable connections between the two rollers for carrying the clothes around them, substantially as described. 30

In testimony whereof I affix my signature in presence of two witnesses.

JAMES E. HARTMAN.
